UNITED STATES PATENT OFFICE.

GUSTAVE O. DEGENER, OF HARTFORD, CONNECTICUT, ASSIGNOR TO ROYAL TYPE-
WRITER COMPANY, INC., OF NEW YORK, N. Y., A CORPORATION OF NEW YORK.

TYPEWRITING MACHINE.

Application filed May 18, 1923. Serial No. 639,867.

To all whom it may concern:

Be it known that I, GUSTAVE O. DEGENER, a citizen of the United States, residing at Hartford, in the county of Hartford and State of Connecticut, have invented certain new and useful Improvements in Typewriting Machines, of which the following is a specification.

This invention relates to typewriting machines in which there is a relative movement between the printing members and the platen for case printing. In some machines the platen is shifted for this purpose, while in others the type bars with their segment 15 or support are thus shifted.

In the Royal standard machine the platen is shifted vertically for case printing, one or more shift keys being connected with the carriage by mechanism which normally holds the carriage in lower position, but which when a shift key is depressed causes the carriage and its platen to be raised to upper case printing. In the Royal machine in order to partially counterbalance the 20 weight of the carriage so that the load on the shift keys may be reduced, a horizontally arranged spring is employed which is connected with the shift mechanism and is put under such tension as to tend to raise the 25 carriage and to thus assist in the shifting operation. In the Royal standard machine the carriage is returned to normal position solely by gravity, as the counterbalancing spring is relatively inactive when the carriage is shifted to its full extent.

In the pending application filed by Edward B. Hess Jan. 13, 1923, No. 612,452, the pending application of Bernard J. Dowd filed Jan. 11, 1923, No. 612,117, and the 40 pending application of Lewis C. Myers filed Feb. 12, 1923, No. 618,576, mechanism is shown, described and claimed whereby an initial impulse is given to the return movement of the carriage by what is known as 45 a repulser. In this way the return of the carriage is quickened and the strength of the counterbalancing spring may be increased so that the shift key may be operated with a lighter touch.

According to my invention I employ repulser mechanism for assisting the return movement of the carriage only when the machine is operated rapidly. When the machine is operated slowly, i. e., when a shift 55 key is depressed slowly, the repulser mechanism is not brought into action.

I have embodied in the machine illustrated in the accompanying drawings a counterbalancing spring constructed and arranged somewhat differently from those heretofore employed. Instead of employing the usual horizontally arranged counterbalancing spring I preferably employ one or more vertically arranged springs so mounted and connected that the spring partially counterbalances the weight of the carriage and where a plurality of vertical springs is employed, they are arranged vertically on opposite sides of the center of gravity of the carriage. Said springs are connected directly to rigid parts of the shift frame instead of being connected to levers as in the usual construction.

Although my invention is applicable to typewriting machines in general in which there is a relative movement between the printing members and the platen, it is particularly serviceable in machines of the Royal type in which the platen is mounted in a carriage which is shifted vertically for case printing. The mechanism containing a preferred embodiment of my invention includes means whereby the shift key is cushioned in a novel way during its depression.

In the drawings:—

Figure 1 is a view in longitudinal vertical cross section of a typewriting machine of the Royal type, showing so much of the usual mechanism as is necessary to illustrate how my invention may be embodied in such mechanism. All parts shown are in lower case position.

Figure 2 is a detail view of parts of the repulser mechanism and parts of the shift key cushioning mechanism.

Figure 3 is a detail view of a part of one of the shift levers.

Figure 4 is a side elevation of the repulser mechanism and parts associated therewith, showing the condition of the repulser mechanism when in operation, i. e., after a shift key has been depressed rapidly. This figure of the drawings also shows the condition of the cushioning devices when the shift frame has been raised to its full extent and just before the shift key has been further depressed.

Figure 4^a is a side view of portions of the repulser mechanism showing the position of the parts when the shift key is operated slowly.

Figure 5 is a view similar to Figure 4, showing particularly the condition of the cushioning mechanism during the cushioning period.

5 Figure 6 is a side view showing the mechanism on the right hand side of the machine. It will be observed that on the right hand side of the machine the cushioning devices and the repulser mechanism are not used 10 although if preferred such mechanism may be duplicated, that is, employed on both sides of the machine.

Figure 7 is a view in vertical section illustrating particularly how the counterbalancing springs are mounted and attached.

15 Figure 8 is a side view of one member of the frame to which the lower ends of the counterbalancing springs are attached.

20 Figure 9 is a side view of the other member of said frame. Fig 9^a is an edge view of the frame member shown in Fig. 9.

The drawings show only so much of a typewriting machine structure as is necessary to indicate how my invention may be 25 applied to the preferred form of machine. The machine frame is indicated at A, the carriage at B, and the platen at C. The shift rail D has short downwardly extending legs E connected near their upper ends 30 to arms F pivoted at f to the legs E and at f' to the machine frame. The lower ends of the legs E are pivotally connected at g to shift levers G which are pivoted to the sides of the machine frame at g'.

35 The carriage is held in lower case position by a latch H connected by a link H' with the vertical arm k of a shift lever K. When the shift key is in raised position, the latch engages a bracket H² on the shift 40 frame and holds said frame against vertical movement. When the shift frame is in raised position, it is thus held if desired by means of a lever L adapted to engage the bracket H² and connected by a link L' with the vertical arm l of a shift lock lever L². Parts of the shift lock mechanism are 45 indicated at M and all of the parts hereinbefore described are of usual construction.

The upward movement of the shift frame 50 is limited by one or more stops N and the downward movement of the carriage is limited by stops N'. These stops are also of well known construction.

In order to approximately counterbalance 55 the weight of the carriage and parts moving therewith, I employ springs which instead of being arranged horizontally as heretofore are arranged vertically. Preferably two such vertical springs are used on each 60 side of the machine and they are preferably arranged on opposite sides of the center of gravity of the carriage as shown and indicated by the dotted line X in Figure 1. Each vertical counterbalancing spring O is 65 attached at its upper end to a flanged plate

O' secured to the machine frame, the two springs being arranged on opposite sides of the center of gravity of the carriage, and each spring is attached at its lower end to an adjustable frame member P which is vertically adjustable by means of screws p on a frame member P' attached to the leg E of the carriage shift frame at g. The springs O are normally under tension and approximately counterbalance the weight of the carriage and parts connected therewith so that the load on the shift key is very small when it is operated. It will be observed that the springs are so arranged as to pull on the shift frame in such manner as to tend to raise it. When the shift frame is raised for case shifting, the tension of the springs is relaxed and, therefore, the springs O do not tend to lower the carriage at any time. The frame members P and P' are shown detached in Figures 8 and 9. It will be observed that the member P has arms p' extending laterally from its opposite ends and the springs are attached to these arms. The vertical part p² of the frame member P is slotted at p³ to receive the screws p which attach it to the member P'. These screws extend through holes p⁴ in the member P' and engage a locking plate P² shown in Figure 7. The member P' has a vertical portion or leg p⁵ which is connected with the member P as described and it has a laterally extending portion p⁶ shown by dotted lines in Figure 7, from which extends vertically an upper portion p⁷ from the upper end of which extends laterally a flange p⁸. This flange p⁸ bears against the leg E of the carriage shift frame and prevents the member P' from moving laterally out of working position. The bolt p⁹ for securing the member P' to the leg E extends through a bushing g³ in the leg E and on this bushing the shift lever G is pivoted as indicated in Figure 7. The bolt p⁹ thus rigidly attaches the frame member P' to the leg E while the lever G is mounted to move about the axis of this bolt. It will be observed by reference to Figure 9 that the member P' has a hole p¹⁰ to receive the bolt p⁹.

Inasmuch as the springs O are attached at their upper ends to a stationary part O' of the machine frame and at their lower ends to a frame secured to the shift frame, it is obvious that said springs serve as counterbalancing devices in the way above described. The tension of the springs may be adjusted by means of the screws p in an obvious manner.

It is desirable as in other machines that the downward movement of the shift key should be cushioned near the end of its stroke. I have provided novel devices for this purpose. As shown these devices consist of a small bell crank lever Q pivoted at

q to the shift lever *G* and connected at its lower end to a link *Q'* which is in turn connected to the arm *k* of the shift key *K*. As indicated at *q'* there is some lost motion between the end of the link *Q'* and the lever *Q* in order that the latch *H* may be withdrawn from the carriage frame before the shift lever *G* is operated to raise the carriage. A spring *Q²* connects the upper rearwardly extending arm of lever *Q* with a rearwardly extending arm *g²* of the lever *G* and tends to rock the lever *Q* on this pivot and to draw the rod or link *Q'* rearwardly and thus slightly raise the shift key. When the shift key is being depressed to its full extent, as indicated in Figure 5, after the carriage has been raised its depression is resisted by the spring *Q²* which thus acts as a cushion to the shift key when said key is depressed during the cushioning period in the manner indicated in Figure 5. This cushioning operation occurs whether the shift key is operated slowly or rapidly. The rearwardly extending arm of the lever *Q* is notched as shown in order that the tension of the spring *Q²* may be adjusted to vary the cushioning effect. It will be observed that the lower arm of the lever *Q* has flanges *q³* (Fig. 2) at front and rear ends between which extends a projection *q⁴* on the shift lever *G*. In this way the movement of the lever *Q* is limited within proper bounds.

When the machine is operated slowly, the depression of a shift key raises the carriage with a light touch inasmuch as the springs *O* approximately counterbalance the weight of the carriage and the carriage is returned to normal position solely by its weight, i. e., by gravity, but when the machine is used by a rapid operator, it is desirable that the carriage should be returned quickly when passing from upper case to lower case position. As before stated, mechanism has heretofore been provided for this purpose, but such mechanism operates in the same way for a slow operator as for a rapid operator. According to my present invention, the repulser mechanism operates only when the shift key is depressed rapidly, and without any adjustment it automatically remains out of operation when the key is depressed slowly.

A two arm lever *R* is pivoted at *r* to the front end of one of the shift levers *G*. This lever *R* has a forwardly extending arm *r'* and a rearwardly extending arm *r²*, the latter arm being notched at its rear end as indicated at *x*. The forwardly extending arm *r'* of the lever *R* is connected to the upper end of a spring *S* which is secured at its lower end to a bracket *T* attached to the machine frame. Within the spring is a small cylinder *U* of rubber, leather, or similar soft material. This cylinder rests on an adjustable screw *U'* and when in normal position as shown in Figure 1, the forwardly

extending arm *r'* of the lever *R* rests on top of this cylinder. When the machine is operated slowly, the repulser spring *S* is not brought into operation, but when the shift key is depressed rapidly, the spring *S* is extended and assists the return movement of the carriage. The rearwardly extending arm *r²* is adapted at times to engage a latch *W* pivoted at *q* to the shift lever *G* and held in normal position by a spring *w*, the upper end of which is attached to the arm *g²* of the shift lever *G*. When in lower case position the lever *R* does not engage the latch *W*, but when the shift key is operated rapidly a sudden upward movement is given to the front end of the lever *G* and this sudden movement of the lever *G* causes the lever *R* to turn on its pivot, its front end being restrained by the spring *S* (which does not then become active) and its rear end being moved into engagement with the latch. In other words, when the mechanism is operated rapidly the arm *r'* of the lever *R* is moved downwardly relatively to the upward movement of the shift lever *G* which carries the latch *W* and thus the lower arm *r²* of the lever *R* is moved towards the latch which it engages and continues so engaged when the shift frame is raised in the manner indicated in Figures 4 and 5. During its movement the spring *S* is placed under tension, which tension is gradually increased as the carriage rises and when the shift key is released, the repulser spring, having considerable power stored in it, gives a quick impulse to the return movement of the carriage, thus effecting when rapidly used in this way a material increase in the rapidity of the typewriting operation.

It will be observed that the repulser mechanism automatically accommodates itself to the slow and rapid operator without any adjustment of any of the mechanism being effective to rapidly return the carriage to lower case position when the machine is operated rapidly or to remain out of operation when the machine is operated slowly.

Figure 6 of the drawings shows the right hand side of the machine where the second shift key *K'* is located. It will be observed that the key *K'* is attached to a rod or shaft *K²* to which the shift key on the left hand side of the machine is attached. While I prefer to employ counterbalancing springs *O* on both the right hand and left hand side of the machine, springs arranged at one side only of the machine may be employed.

I claim as my invention:—

1. In a typewriting machine, a case shift mechanism having a shift key and equipped with repulser devices, and means to render said devices effective only when the shift key is rapidly depressed.
2. In a typewriting machine, a case shift mechanism having a shift key and equipped

with a repulser spring, and means to render said spring effective only when the shift key is rapidly depressed.

3. In a typewriting machine, case shift mechanism including a shift lever operated by the shift key to raise the platen carriage, a two-armed lever pivotally connected with the shift lever, a repulser spring connected with one end of the two-armed lever, and 10 a latch carried by said shift lever with which an arm of the two-armed lever is adapted to engage.

4. In a typewriting machine, case shift mechanism including a shift lever operated by a shift key to raise the platen carriage, a two-armed lever pivotally connected with said shift lever, a repulser spring connected with one end of the two-armed lever, a latch carried by the shift lever with which the 20 two-armed lever is adapted to engage, and a buffer associated with the repulser spring and which is adapted to engage said two-armed lever.

5. In a typewriting machine, case shift mechanism including a shift lever operated by a shift key to raise the platen carriage, a two-armed lever pivotally connected with said shift lever, a repulser spring connected with one end of the two-armed lever, a 30 latch carried by the shift lever with which the two-armed lever is adapted to engage, a buffer associated with the repulser spring and which is adapted to engage said two-armed lever, and means for adjusting the 35 position of said buffer.

6. In a typewriting machine, case shift mechanism including a shift lever pivotally connected with the machine frame and pivotally connected with the shift frame, a 40 two-armed lever pivotally connected with the shift lever, a repulser spring to which one arm of the lever is connected, and a latch pivotally connected with the shift lever and adapted at times to engage the 45 two-armed lever.

7. In a typewriting machine, carriage shift mechanism comprising a shift frame,

a shift key, a shift lever pivotally connected with the machine frame and with the shift frame, a spring pressed two-arm lever pivotally connected with the shift lever, and a link connecting the two-armed lever with the shift key. 50

8. In a typewriting machine, carriage shift mechanism comprising a shift frame, a shift key, a shift lever pivotally connected with the machine frame and with the shift frame, a spring pressed two-arm lever pivotally connected with the shift lever, and a link connecting said two armed lever 60 with the shift key, said shift lever having a lug near one end arranged between flanges on said two-armed lever.

9. In a typewriting machine, carriage shift mechanism comprising a shift frame, a shift key, a shift lever pivotally connected with the machine frame and with the shift frame, a spring pressed two-arm lever pivotally connected with the shift lever, and a link extending from the shift lever and 70 having a lost motion connection with the two-armed lever. 65

10. In a typewriting machine, a carriage, a shift frame on which the carriage is supported, vertically arranged counter- 75 balancing springs arranged on opposite sides of the center of gravity of the carriage and connected at their upper ends to the machine frame and at their lower ends to a part of the shift frame. 80

11. In a typewriting machine, a carriage, a shift frame on which the carriage is supported, vertically arranged counterbalancing springs connected at their upper ends with the machine frame, and means for connecting the lower ends of said springs to the shift frame comprising a member attached to the shift frame and another member to which the lower ends of the springs are attached which is vertically adjustable on 85 said first mentioned member. 90

In testimony whereof, I have hereunto subscribed my name.

GUSTAVE O. DEGENER.
